US0D1046899S

(12) **United States Design Patent** (10) Patent No.: **US D1,046,899 S**
(45) Date of Patent: ** Oct. 15, 2024

(54) **DISPLAY SCREEN OR A PORTION THEREOF WITH A GRAPHICAL USER INTERFACE**

- (71) Applicant: **IGT**, Las Vegas, NV (US)
(72) Inventor: **Patrick Roussety**, South Melbourne (AU)
(73) Assignee: **IGT**, Las Vegas, NV (US)
(**) Term: **15 Years**
(21) Appl. No.: **29/929,924**
(22) Filed: **Feb. 26, 2024**

Related U.S. Application Data

- (60) Continuation of application No. 29/905,602, filed on Oct. 23, 2023, which is a division of application No. 29/820,303, filed on Dec. 21, 2021, now Pat. No. Des. 1,009,075.

(57) **CLAIM**

The ornamental design for a display screen or a portion thereof with a graphical user interface as shown and described.

DESCRIPTION

The FIGURE is a front view of a display screen or a portion thereof with a graphical user interface showing my new design.

The dashed broken line perimeter in the drawing illustrates a display screen or a portion thereof and forms no part of the claimed design. The remaining dashed broken lines in the drawing illustrate portions of the graphical user interface that form no part of the claimed design.

1 Claim, 5 Drawing Sheets
